US00D989155S

(12) **United States Design Patent** (10) **Patent No.:** **US D989,155 S**
(45) **Date of Patent:** **** Jun. 13, 2023**

(54) **CAMERA**

(71) Applicant: **Google LLC**, Mountain View, CA (US)

(72) Inventors: **Moonchul Kim**, Mountain View, CA (US); **Sung Bai**, San Jose, CA (US); **Maj Isabelle Olsson**, Sunnyvale, CA (US); **Étienne Bérubé**, San Francisco, CA (US)

(73) Assignee: **GOOGLE LLC**, Mountain View, CA (US)

(**) Term: **15 Years**

(21) Appl. No.: **29/846,184**

(22) Filed: **Jul. 14, 2022**

Related U.S. Application Data

(63) Continuation of application No. 29/756,322, filed on Oct. 27, 2020, now Pat. No. Des. 962,322.
